(57) **CLAIM**

The ornamental design for a teether bib, as shown and described.

DESCRIPTION

FIG. 1 is a front elevational view of a teether bib showing our new design;

FIG. 2 is a bottom view;

FIG. 3 is a rear elevational view;

FIG. 4 is a side elevational view thereof;

FIG. 5 is an enlarged fragmentary side view showing an alternate embodiment of the design shown in FIG. 1; and, FIG. 6 is a front elevational view of FIG. 5.

The jagged broken lines which define the boundary of the claimed design, form no part thereof. The broken, (dashed) lines around the periphery of the bib, teether and neck opening, are understood to represent stitching. And the remaining broken lines showing environmental subject matter, form no part of the claimed design.
